CLAIM

The ornamental design for an end panel insulator for temperature-controlled rotary cylinder, as shown and described.

DESCRIPTION

FIG. 1 is a perspective view of an end panel insulator for a temperature-controlled rotary cylinder showing our new design.

FIG. 2 is a back elevational view thereof;

FIG. 3 is a side elevational view thereof;

FIG. 4 is a side elevational view thereof, opposite to that illustrated in FIG. 3;

FIG. 5 is a front elevational view thereof with the closure flap closed from right to left;

FIG. 6 is a front elevational view thereof, with the closure flap closed from left to right;

FIG. 7 is a perspective view of a second embodiment of an end panel insulator for a temperature-controlled rotary cylinder showing our new design;

FIG. 8 is a back elevational view thereof;

FIG. 9 is a side elevational view thereof;

FIG. 10 is a side elevational view thereof, opposite to that illustrated in FIG. 9;

FIG. 11 is a front elevational view thereof, showing the closure flap closed from left to right; and

FIG. 12 is a front elevational view thereof, showing the closure flap closed right to left.

The pattern shown in FIGS. 2 and 8 represents quilted insulation material.
